(57) CLAIM

The ornamental design for a dispenser, as shown and described.

DESCRIPTION

FIG. 1 is a perspective view of a dispenser, illustrating my new design;

FIG. 2 is a front elevation view thereof, the back elevation view is a mirror image of the front;

FIG. 3 is a right side elevation view thereof, the left side elevation view is a mirror image of the right side;

FIG. 4 is a top elevation view thereof; and,

FIG. 5 is a bottom elevation view thereof.

The broken lines shown in the figures are included for purposes of illustrating portions of the article and form no part of the claimed design.
